UNITED STATES PATENT OFFICE

2,329,484

SEWING MACHINE

Oscar Quist, Chicago, Ill., assignor to Union Special Machine Company, Chicago, Ill., a corporation of Illinois

Application March 30, 1940, Serial No. 326,828

19 Claims. (Cl. 112—206)

This invention relates to sewing machines, and has reference more particularly to sewing machines of the kind typified in U. S. Patent 2,189,656 granted to George Sauer on February 6, 1940, wherein the needle is moved laterally while in the work to assist the feed dog in its work advancing action.

My invention has for one of its aims to simplify the needle and feed actuating means of such machines, with a view toward reducing manufacturing and assembling costs, and toward securing more silent and efficient operation. This objective I attain as hereinafter more fully disclosed, by coordinating the needle and feed operating means for actuation by a single rotary actuator.

In connection with a sewing machine having the above attributes, I further aim to make it possible, through provision of a single regulating means such as hereinafter disclosed, whereby the feeding movements of the needle and the feed dog may be compensatively and simultaneously increased or decreased to vary the stitch length.

Other objects and corresponding advantages of my invention will appear from the following detailed description of the attached drawings, wherein is shown a silent and adjustable sewing machine.

Fig. 1 is a view, partly in front elevation and partly in longitudinal section, of a sewing machine conveniently embodying the present improvements.

Fig. 2 shows the machine in inverted plan with the cover of its oil sump removed to expose important parts within the machine frame.

Figs. 3 and 4 are transverse sections taken as indicated, respectively, by the angled arrows III—III and IV—IV in Figs. 1 and 2.

Fig. 5 is a fragmentary view in side elevation showing the regulating means by which the feeding movements of the needle and the feed dog can be adjusted; and

Fig. 6 is a view, partly in perspective and partly in section, showing the regulating means and certain parts of the needle and feed actuating mechanism.

The frame of the sewing machine herein illustrated provides a horizontal work support 10 wherefrom rises, at one end, a hollow standard 11, which sustains an overhanging needle arm 12 having a needle head 13 at its free end. From Fig. 1, it will be noted that the side walls of the standard 11 are continued below the work support 10 to provide an oil sump 15 which is closed at the bottom by a removable cover plate 16. Set into spaced transverse partitions 17 and 18 with

in the arm 12 are bearing bushings 19 and 20 wherein is journaled an oscillating sleeve 21; and set in turn into the opposite ends of said sleeve are bushings 22 and 23 which serve as bearings for a shaft 25. As shown at the right of Fig. 1, the shaft 25 extends to the exterior of the machine frame to a bearing bushing 26 in the outer side wall of the standard 11 and on the protruding end thereof is mounted a combined hand wheel and pulley 27 by which the machine can be driven either manually or under power. The needle bar 28 of the machine is slidably guided in a carrier 29, which, see Figs. 1 and 3, is suspended from a pivot stud 30 secured in a bore 31 within the needle head 13 well above the level of the shaft 25. As shown in Fig. 1, the needle bar carrier 29 is yoked at its lower end to expose a portion of the needle bar 28 for attachment thereto of a collar 32 with a rearwardly projecting stud 33, which, through a pitman 35, is connected to a balanced actuating crank member 36 on the end of the shaft 25 within the needle head. By the means just described, endwise reciprocatory movements are imparted to the needle bar 28 in a generally well known manner, whereby the needles 37 at the lower end of said bar are passed up and down through a throat plate 38 (Fig. 3) set into the work support 10. Secured to the left hand end of the sleeve 21 within the needle head 13 is a pendant arm 40, which, through a horizontal link 41, is coupled with the needle bar carrier 29. Thus, as the sleeve 21 is oscillated, the needle bar is swung laterally in the direction of feeding about the fulcrum axis 30 of the carrier 29. Arranged to cooperate with the needles 37 in the stitch formation below the work support 10, is a pair of vertical axis rotary hooks 42. Secured to the shafts 43 of the rotary hooks 42 are spiral gear pinions 44 which mesh respectively with spiral gears 45 on a rotating shaft 46 suitably journaled in the machine frame below the work support. From Figs. 1 and 2 it will be noted that the shaft 46 extends through a bearing 47 into the oil sump 15; and moreover that it is driven, through a train of spur gears 48, 49 and 50 within the hollow of the standard 11, from the power shaft 25, the ratio of the gears being such that the two shafts are rotated in the same direction and at the same speed. Operating upwardly through slots in the throat plate 38 is a feed dog 51 which is adjustably secured to the feed bar 52. This feed bar 52 has an arm which underreaches the shaft 46 and which is connected to the strap link 53 of an eccentric 54 on said shaft, with the result that up

and down or lift movements are imparted to said bar. At its rear end, the feed bar 52 is pivotally connected to a pin 55 at the top of a vertical rocker 56. This rocker 56 is mounted on a shaft 57 which extends parallel with the shaft 46 below the work support 10 and which is likewise suitably journaled in bearings provided by the machine frame. Also, like the shaft 46, the shaft 57 extends through a bearing 58, see Fig. 2, into the oil sump 15, and there secured to it is an arm 59, see Fig. 4. By means of a vertical link 60, the arm 59 is connected to the horizontal extremity 61 of a bell crank lever 62 secured to the right hand end of the sleeve 21, see Fig. 1 within the standard 11. The dependent arm 63 of the bell crank lever 62 is pivotally connected at 64 to a clevis sleeve 65 which is slidable on the lower end 66 of a rocker 67 whereof the fulcrum is indicated at 68. The upper portion 69 of the rocker 67 is engaged by a sleeve 70 having a lateral strap portion 71 engaging an eccentric 72 on the shaft 25 within the standard 11 between the bell crank 62 and the spur pinion 50. The fulcrum 68, see Fig. 4, has its ends secured in a yoke collar 73 at the lower end of a cylindrical slide 74 confined for endwise shifting in a boss 75 at the front of the standard 11. The slide 74 is internally threaded for engagement by a regulating screw 76 having a manipulating knob 77 at its upper end. Secured by set screws 78 vertically within a bore in the boss 75 alongside the bore for the slide 74, is a rod 79 which extends above said boss and which has its upper end bent laterally and forked, as at 80, to engage between the manipulating knob 77 and a shoulder adjacent the top of the screw 76. As shown in Fig. 6, the collar 73 is formed with a lateral lug projection 81 at right angles to its clevis which engages a longitudinal slot 82 in the lower end of the rod 79 whereby the slide 74 is held against rotation in the boss 75. A set screw 83 serves to prevent displacement of the slide 74 in vertically adjusted positions.

Operative to oppose the feed dog 51 is a presser foot 84 which is pivoted at 85 to a shank member 86 secured to the lower end of a presser bar 87. After more or less common practice, the presser bar 87 is guided for endwise movement in the needle head 13 of the machine and is subject to the pressure of a helical spring 88. At its lower end the spring 88 bears upon a collar 89 secured to the presser bar 87 within the needle head 13, and, at its top abuts the lower end of a guide bushing 90 which is screwed into the needle head 13 from above and which has a manipulating knob 91 on its protruding end. In order that the presser foot 84 may be elevated for convenience of initially inserting the work beneath it, there is provided a control means, including a rock shaft 92 which is suitably journaled in the partitions 17, 18 within the hollow of the needle arm 12. Secured to the rock shaft 92 within the needle head 13 is an arm 93 whereof the end is connected, by means of a link 95, with the collar 89 on the presser bar 87; and secured to said shaft within the central hollow of the needle arm 12 is a lever 96 which projects horizontally outward through a clearance opening in the rear side of the needle arm 12 for connection thereof, through means of a link rod shown at 97 in Figs. 3 and 4 to a suitable knee press or foot treadle, not illustrated.

The operation of the machine is as follows:

By action of the eccentric 72 on the upper rotating shaft 25, the double ended rocker 67 is constantly oscillated about the fulcrum pin 68, and

due to connection of the bell crank lever 62 to the slide collar 65 at the lower end of said rocker, oscillatory movements are concurrently imparted to the sleeve 21 and to the feed rock shaft 57.

As a result, the needle bar carrier 29 is swung to and fro in the direction of feeding in synchronism with impartation of feed movements to the feed dog 51. Upward adjustment of the fulcrum 68 of the rocker 67 by means of the regulating screw 76 from the position shown in Fig. 4 will obviously be attended by concurrent compensative increase in the amplitude of the needle swing and the feeding movement of the feed dog 51, while, conversely, downward adjustment of said fulcrum will be attended by compensative decrease in the amplitude of the needle swing and shortening of the feeding stroke of the feed dog 51. Such adjustments are facilitated by virtue of the provision of numbered graduations (Figs. 5 and 6) on the protruding upper end of the gauge bar 79 for coordination with the top of the cylindric slide 74.

The parts within the standard 11 are all lubricated with oil dispersed by the transmission gear train whereof the lower wheel 43 dips into a supply of oil at the bottom of the sump 15 which is normally maintained at the level indicated at L in Fig. 1. The bearings 19 and 20 for the sleeve 21 are individually lubricated with oil introduced by way of vertical ducts 98 and 99 in the partitions 17 and 18 below a retractable cover 103, some of such oil finding its way to the inner bearings 22 and 23 for the shaft 25 by way of communicating ports shown at 100 and 101 respectively in Fig. 1. The intermediate chamber within the overhanging arm 12 may be utilized, as shown, to house the needle thread tensions 102 which are accessible upon retraction of the cover 103.

Having thus described my invention, I claim:

1. A sewing machine, comprising an endwise reciprocative needle bar; a carrier guide for the needle bar suspended from a fixed pivot for movement to and fro laterally in the line of feed; a work feeding member; a rotary shaft with means for reciprocating the needle bar in its carrier guide; an oscillatable sleeve coaxial with the shaft; means for oscillating the sleeve; and means connecting the sleeve with the needle bar carrier guide and the feed member for concurrent actuation thereby.

2. A sewing machine according to claim 1, wherein the needle carrier guide is suspended from a stationary pivot stud in the needle head wall above the level of the rotary shaft.

3. A sewing machine according to claim 1, wherein the sleeve is oscillated through connections interposed between it and the rotary shaft.

4. A sewing machine according to claim 1, wherein the means for oscillating the sleeve includes a bell crank lever on the latter, a rotary actuator on the shaft, and means connecting said lever to the rotary actuator.

5. A sewing machine according to claim 1, wherein the means for oscillating the sleeve includes a lever on the latter, an eccentric on the rotary shaft, a medially fulcrumed rocker bar, a collar slidable along one end of the rocker bar and pivotally connected to the lever, another collar slidable along the other end of the rocker bar and having a strap connection with the eccentric on the shaft.

6. A sewing machine according to claim 1, wherein the means for oscillating the sleeve includes a lever on the latter, an eccentric on the

rotary shaft, a medially fulcrumed rocker bar, a collar slidable along one end of the rocker bar and pivotally connected to the lever, another collar slidale along the other end of the rocker bar and having a strap connection with the eccentric on the shaft; said machine further comprising means for shifting the fulcrum for the rocker bar to vary the oscillatory movements of the sleeve and in turn the lateral movements imparted to the needle bar carrier guide.

7. A sewing machine according to claim 1, wherein the means for oscillating the sleeve includes a lever on the latter, an eccentric on the rotary shaft, a medially fulcrumed rocker bar, a collar slidale along one end of the rocker bar and pivotally connected to the lever, another collar slidale along the other end of the rocker bar and having a strap connection with the eccentric on the shaft; said machine further comprising means for shifting the fulcrum for the rocker bar to vary the oscillatory movements of the sleeve and in turn the lateral movements imparted to the needle bar carrier guide, the latter means including a slide which supports the fulcrum for the rocker bar and which is confined in a fixed portion of the machine, and regulating means for shifting said slide.

8. A sewing machine according to claim 1, wherein the means for oscillating the sleeve includes a lever on the latter, an eccentric on the rotary shaft, a medially fulcrumed rocker bar, a collar slidale along one end of the rocker bar and pivotally connected to the lever, another collar slidale along the other end of the rocker bar and having a strap connection with the eccentric on the shaft; said machine further comprising means for shifting the fulcrum for the rocker bar to vary the oscillatory movements of the sleeve and in turn the lateral movements imparted to the needle bar carrier guide, the latter means including a slide which supports the fulcrum for the rocker bar and which is confined in a fixed portion of the machine, and a regulating screw held against endwise movement and threadedly engaging said slide.

9. A sewing machine comprising, in combination, a vertical needle bar; work feeding means; a carrier guide for the needle bar movable to and fro laterally in the line of feed; a rotary horizontal shaft with an actuator thereon for imparting endwise movement to the needle bar; an oscillatable sleeve surrounding the shaft; separate connections interposed between the sleeve and the work feeding means and the needle bar carrier guide for actuation thereof in synchronism; and means for oscillating the sleeve.

10. A sewing machine according to claim 9, wherein the means for oscillating the sleeve includes a lever on the latter, an eccentric on the rotary shaft, a medially fulcrumed rocker bar, a collar slidale along one end of the rocker bar and pivotally connected to the lever, another collar slidale along the other end of the rocker bar and having a strap connection with the eccentric on the shaft; wherein the feeding means includes a horizontally reciprocating feed dog; and wherein the interposed connections for actuating the feed dog derive their movement from the lever.

11. A sewing machine according to claim 9, wherein the means for oscillating the sleeve includes a lever on the latter, an eccentric on the rotary shaft, a medially fulcrumed rocker bar, a collar slidale along one end of the rocker bar and pivotally connected to the lever, another

collar slidale along the other end of the rocker bar and having a strap connection with the eccentric on the shaft; wherein the feeding means includes a horizontally reciprocating feed dog; wherein the interposed connections whereby the feed dog is actuated in synchronism with the needle bar carrier guide derive their movement from the lever; and wherein there is means for shifting the fulcrum for the rocker bar to vary the oscillatory movements of the sleeve and in turn the feeding movements of the needle and the feed dog.

12. A sewing machine comprising, in combination, a frame with a work support and a horizontal arm overhanging the work support; a horizontal rotary shaft journaled on said arm; a vertical needle bar; means whereby the needle bar is reciprocated endwise from the rotary shaft; a carrier guide for the needle bar supported at the end of the overhanging arm with capacity for being moved to and fro laterally in the direction of feeding; an oscillating sleeve surrounding the shaft; interposed connections at the free end of the overhanging arm whereby the needle bar carrier guide is moved as aforesaid from the sleeve; means at the anchorage end of the overhanging arm for oscillating the sleeve including a lever on the latter, an eccentric on the rotary shaft, a medially fulcrumed rocker bar, a collar slidale along one end of the rocker bar and pivotally connected to the lever, and another collar slidale along the other end of the rocker bar and having a strap connection with the eccentric on the shaft; a feed dog operative upward through the work support at the region of stitch formation; a rock shaft extending longitudinally of the machine and having a rocker thereon for imparting horizontal feed movements to the feed dog; and a connection extending down from the lever aforesaid to the feed rock shaft whereby the feed movements are imparted to the feed dog in synchronism with the to and fro movements of the needle bar carrier guide.

13. A sewing machine according to claim 12, wherein the overhanging frame arm is hollow and sustained by a hollow standard from one end of the work support; wherein the feed rock shaft extends into a downward prolongation of the standard below the work support; wherein the rotary shaft, the sleeve and the needle bar and the carrier guide actuating parts are all enclosed within the hollow of the overhanging arm; and wherein the sleeve oscillating parts and the downward connection from the lever to the feed bar rocker shaft are all housed within the standard.

14. A sewing machine according to claim 12, wherein the overhanging frame arm is hollow and sustained by a hollow standard from one end of the work support; wherein the feed rock shaft extends into a downward prolongation of the standard below the work support; wherein the rotary shaft, the sleeve and the needle bar and the carrier guide actuating parts are all housed within the hollow of the overhanging arm; and wherein the sleeve oscillating parts and the downward connection from the lever to the feed bar rocker shaft are all housed within the standard; and wherein means takes lubrication oil from a sump in the bottom of the standard and disperses it to automatically lubricate the parts enclosed in said standard.

15. A sewing machine according to claim 12, wherein the overhanging frame arm is hollow and sustained by a hollow standard from one end of

the work support; wherein the feed rock shaft extends into a downward prolongation of the standard below the work support; wherein the rotary shaft, the sleeve and the needle bar and the carrier guide actuating parts are all enclosed within the hollow of the overhanging arm; wherein the sleeve oscillating parts and the downward connection from the lever to the feed bar rocker shaft are all housed within the standard; wherein looper means cooperate with the needle below the work support; wherein a rotary loop actuating shaft extends longitudinally beneath the work support and enters the downward prolongation of the standard; wherein a train of gears connects the looper actuating shaft with the first mentioned rotary shaft; and wherein one of the gears of the train dips into a supply of oil in the bottom of the standard and disperses it to automatically lubricate the parts within the standard.

16. A sewing machine according to claim 12, wherein the overhanging frame arm is hollow and sustained by a hollow standard from one end of the work support; wherein the feed rock shaft extends into a downward prolongation of the standard below the work support; wherein the rotary shaft, the sleeve, the needle bar and the carrier guide actuating parts are all housed within the hollow of the overhanging arm; and wherein the sleeve oscillating parts and the downward connection from the lever to the feed bar rocker shaft are all housed within the standard; and wherein means is provided for shifting the fulcrum for the rocker bar to vary the oscillatory movements of the sleeve and in turn the feed movements imparted to the needle and the feed dog.

17. A sewing machine according to claim 12, wherein the overhanging frame arm is hollow and sustained by a hollow standard from one end of the work support; wherein the feed rock shaft extends into a downward prolongation of the standard below the work support; wherein the rotary shaft, the sleeve, and the needle bar and the carrier guide actuating parts are all housed within the overhanging arm; and wherein the sleeve oscillating parts and the downward connection from the lever to the feed bar rocker shaft are all housed within the standard; and

wherein means is provided for shifting the fulcrum for the rocker bar to vary the oscillatory movements of the sleeve and in turn the feed movements imparted to the needle and the feed dog, the latter means including a slide confined to vertical movement in a lug at the side of the standard, and regulating means accessible at the exterior of the standard for adjusting the slide.

18. A sewing machine according to claim 12, wherein the overhanging frame arm is hollow and sustained by a hollow standard from one end of the work support; wherein the feed rock shaft extends into a downward prolongation of the standard below the work support; wherein the rotary shaft, the sleeve, the needle bar, and the carrier guide actuating parts are all housed within the hollow of the overhanging arm; wherein the sleeve oscillating parts and the downward connection from the lever to the feed bar rocker shaft are all housed within the standard; wherein means is provided for shifting the fulcrum for the rocker bar to vary the oscillatory movements of the sleeve and in turn the feed movements imparted to the needle and the feed dog, the latter means including a slide confined to vertical movement in a lug at the side of the standard, and regulating means accessible at the exterior of the standard for adjusting the slide.

19. In a sewing machine, a work support; a rotary drive shaft; stitch forming mechanism including an axially reciprocative needle which passes down through the work support and complemental instrumentalities to cooperate therewith below the work support; work feeding means including a presser foot and an opposing four motion feed dog; and mechanism for simultaneously actuating the feed dog and imparting work feeding movements to the needle, said mechanism including a rotary actuator on the drive shaft, a member oscillated by said actuator, operating connections interposed between the member and the feed dog, and separate operating connections extending between said member and the needle, the last mentioned connections including a sleeve coaxial with the drive shaft.

OSCAR QUIST.
